UNITED STATES PATENT OFFICE.

SIMON G. SETTLES, OF SEATTLE, WASHINGTON, ASSIGNOR, BY DIRECT AND MESNE ASSIGNMENTS, TO HERBERT W. BARDET, OF SEATTLE, WASHINGTON.

SINK STRAINER.

Application filed November 4, 1926. Serial No. 146,114.

This invention relates to a refuse strainer for the outlet of a kitchen sink and the like.

The object of my invention, generally stated, is to provide an improved strainer of this character, and means for detachably connecting the same to the sink whereby the strainer is removable for dumping therefrom refuse which is collected within the strainer.

More specific objects and advantages of the invention will appear in the following description.

The invention consists in the novel construction, adaptation and combination of devices hereinafter described and claimed.

In the accompany drawing,—

Figure 1 is a transverse vertical section of a portion of the floor of a kitchen sink with devices embodying the present invention applied thereto. Fig. 2 is a plan view of the strainer and frame members taken together. Fig. 3 is a similar view of the frame member with portions broken away. Fig. 4 is a side elevation of the strainer member, Fig. 5 is a plan view of Fig. 4 and Fig. 6 is a front elevation of the strainer bail shown detached.

In said drawing the reference numeral 10 represents the floor of a sink having a drain opening 11 which is disposed centrally of a recess 12 as hitherto. This recess is of a diameter and depth to accommodate a frame member 13 so that the upper surface of the latter will be in a plane with or slightly below the plane of the upper surface of the sink floor 10. The frame 13 is rigidly secured to the sink as by means of bolts (not shown) engaging in holes such as 14 provided in the frame. Such frame is formed to be provided centrally with a substantially circular opening 15, Fig. 3, with shelf elements 16 and 17 at diametrically opposite sides of the opening.

These shelf elements are disposed in horizontal planes parallel with and below the plane of the surrounding body portion 18 of the frame; said body and shelf elements being connected with each other by a peripheral wall element 19 of the frame.

Medially of the length of the arc of the shelf 16 the wall 19 is provided with an aperture 20 and diametrically opposite thereto above the shelf 17, the body portion 18 of the frame is protruded inwardly as at 21 of the inner circumference of the wall 19 to

provide a catch. Associated with the frame 13 is a bowl shaped strainer 22 having a perforated body portion 23 with a marginal flange or rim disposed, preferably, in two semicircular portions denoted by 24 and 25, which are respectively disposed in parallel horizontal planes which are joined by obliquely arranged rim portions 26. At right angles to a vertical plane passing through the rim portions 26, the rim portion 24 is provided with a protuberance 24¹ which is engageable in the frame aperture 20 when the strainer is in its operative position (Fig. 1) with the strainer rim elements 24 and 25 resting upon the shelf elements 16 and 17 of the frame.

The rim element 25 is formed or cut away, as at 27 Fig. 5, to permit the passage of the strainer rim by the inwardly projecting portion 21 of the frame. Provided in the opposite sides of the strainer body are apertures 28 to receive the extremities of a bail 29, which is of a substantially semicircular shape and is bent as at 30 to provide ends 31 which are disposed at right angles to the plane of the main portion of the bail. The bail ends 31, moreover, are each provided with a notch 32 (Fig. 6) to afford below and above the latter a hook bill 33 and a shoulder 34 which are adapted to engage under and upper surfaces of the strainer rim, to hingedly connect the bail to the strainer, and also furnish stops for limiting the turning of the bail at its upright position, see Figs. 4 and 5 when the bail is utilized when withdrawing the strainer from the sink and in carrying it to a place for dumping refuse therefrom. The bail is shown in Fig. 1 by dotted lines 29^a in its carrying position and by full lines in the position which the bail occupies when the strainer is in place and when thus arranged the bail rests upon the lower portion 17 of the rim and the then upper surface of the bail will be in the plane of the upper rim-surface 16, or nearly so.

In addition to the bail serving as the strainer carrying means it also performs another important function—which is to serve as a latch for engaging under the frame projection 21 to releasably secure the strainer to the frame.

To enable the passage of the bail when moving the same into and from its frame engaging position, the bow of the bail is slightly flattened to reduce its effective dis-

tance from the axis of the bail's connection with the strainer.

29¹ represents a thumb engageable projection on the bail to facilitate taking hold of 5 the same.

It is to be noted that the shape of the bowl or body portion of the strainer has considerably more depth than sink strainers now in general use, which depth is advantageous for two reasons—first to provide 10 large capacity for accumulated refuse and; second, to permit the strainer apertures to be disposed at elevations such as to obviate the likelihood of all of the apertures being 15 choked by material deposited in or upon the strainer as hitherto.

The construction and operation of the invention will be understood from the foregoing description.

20 20 What I claim, is,—

1. A strainer adapted to be used in the drain opening of a sink and extending downwardly below the bottom of the sink, said strainer having a bail hingedly connected 25 thereto, said bail serving as a carrier for the strainer and also as a latch for detachably securing the strainer to the sink.

2. In combination, a sink strainer, a bail 30 provided therefor, a frame for said strainer, said frame being capable of being secured to a sink and provided with a catch which is adapted to be engaged by the bail for detachably securing the strainer to the frame.

3. In combination, a sink strainer, a frame

therefor, adapted to be rigidly secured to a 35 sink, and a latch hingedly connected to the strainer for detachably connecting the latter to the frame.

4. In combination, a sink strainer provided with a marginal rim, an annular frame 40 adapted to receive the strainer and serve as a support therefor, and frame engaging devices connected to the strainer for relative movement with respect to the strainer for detachably securing the latter to said frame. 45

5. In combination, a sink strainer provided with a protuberance, a frame having an opening therein to receive the strainer and serve as a support therefor, said frame being engageable at one side of its opening 50 by said protuberance, and a bail hingedly connected to the strainer and cooperating with said protuberance for detachably securing the strainer to said frame.

6. In combination, a sink strainer having 55 a marginal rim, an annular frame therefor, said frame having about the opening thereof a shelf to receive said rim for supporting the strainer, and a bail attached to the strainer for carrying the same, said bail being adapted to be swung down upon the 60 rim below the plane of the upper surface of the frame to act as a latch for the strainer with respect to the frame.

Signed at Seattle, Washington, this 12th 65 day of October, 1926.

SIMON G. SETTLES.
